UNITED STATES PATENT OFFICE.

WILHELM HÜTTEMANN, OF COLOGNE-LINDENTHAL, GERMANY.

DOOR LOCK.

Application filed July 8, 1920. Serial No. 394,845.

To all whom it may concern:

Be it known that I, WILHELM HÜTTEMANN, a citizen of the German Republic, residing at Cologne-Lindenthal, Germany, have invented certain new and useful Improvements in Door Locks (for which I have filed applications in Germany April 25, 1914, March 5, 1915, February 16, 1916, March 4, 1919, August 4, 1919, September 12, 1919, and Great Britain, October 20, 1919), of which the following is a specification.

The present invention relates to a door-lock of the kind in which the inner door-handle is rotatable relative to the outer one, and consists essentially in the provision of a rotary ring or casing which is coupled to the inner handle and adapted to operate the follower when the handle is pressed in the usual manner, the ring being provided with an arm which, when the handle is turned in the direction opposite to the usual one, serves to arrest the lock mechanism. Means are provided whereby such arrest may affect the bolt itself or merely the outer handle, in which latter case the bolt is left free to engage like an automatic latch and to be withdrawn from the outside by means of a key.

In the accompanying drawings the invention is illustrated by way of example,

Fig. 1 representing a cross-sectional view of the lock according to one construction,

Fig. 2, a longitudinal section of the same,
Fig. 3, a perspective view of the rotary casing,
Fig. 4, a perspective view of an indicating plate, and

Fig. 5, a front view of the latter,

Fig. 6, is a longitudinal section of a lock of a different construction,

Fig. 7, a similar view of a third construction,

Fig. 8, a longitudinal section of the lock-bolt on the line *a*—*b* of Fig. 6,

Fig. 9, a view of the striking plate for the bolt of Fig. 7, and

Fig. 10, a view of a different bolt-head,

Fig. 11 is a side-view of the key-mechanism, and

Fig. 12, a front-view of the same,

Fig. 13 is a view of a lock-mechanism of yet another construction,

Fig. 14, a longitudinal section of the spindle showing further modifications,

Figs. 14^a and 15, views of details of the inner handle showing different modes of arresting the same,

Fig. 16, a longitudinal section of the spindle showing another modification of the elements,

Fig. 17, a view showing an arresting element for the inner handle,

Fig. 18, showing bolt and follower arranged in a different relative position, and

Figs. 19 and 20, views showing details of means for releasing the arrested lock electrically.

The bolt 7 is operated by means of a bell-crank lever 9 (Fig. 2) and a follower 6 which is directly connected to the outer handle 2. The inner handle 1, which is rotatable relative to the outer one, controls a ring 14, through a slot 16 or notch in which the operating arm 8 of the follower projects, the arm being engaged by the ring 14 at one end 16 of the slot for operating the bolt, when the handle is turned in the ordinary manner. The ring 14 carries an arm 13 which, by turning the inner handle backwards, can be placed against a shoulder 15 (Fig. 2) or in a notch 33 (Fig. 6) in the bolt for arresting the latter. According to Figs. 6 to 8, the bell-crank lever, instead of acting directly on the bolt, acts on a slide 30 the inner end 33 of which abuts against a shoulder 32 formed on the slide 30 close to the notch 33. A spring 84, bearing against the inner end of the bolt, tends to maintain bolt and slide in a forward position. The slide 30 has a lug 31 against which the arm 13 can be placed for arresting the slide, and thereby the outer handle, without arresting the bolt, which is therefore free to move in opposition to the spring 84, so that it can be used as an automatically engaging latch. The bolt can also be arrested by turning the arm into engagement with the notch 33 as previously described.

When the outer handle is arrested by dogging the bolt by means of the inner handle, as just described, the latch-bolt can be operated from the outside by means of a key. This key-mechanism, (Figs. 11 and 12) will be of the revolving-barrel type, the barrel having an arm 20^a which acts directly on the bolt for the withdrawal of the same. The key may also be used for arresting the bolt 7, the barrel-arm being for that purpose

turned against a lug 40 formed on the bolt. As it is necessary, in the latter instance, to arrest the barrel in more than one position, the cylinder casing is fitted with two sets of 5 lock-pins 47 and 48 both co-operating with the same key, one securing the barrel in position for arresting the bolt 7, and the other in the position shown in Fig. 6. The barrel may be connected to a casing 42 (Fig. 13) 10 similar to the ring 14, which turns about a hub 43 having the bolt-operating arm 46. One edge 45 of the casing engages the arm 46 for actuating the bolt. When the casing is turned in the opposite direction, an arm 44, 15 connected to the casing, is placed against a lug 41 on the bolt for arresting the latter.

To retain the inner handle in its various 20 positions, a spring-pressed push pin 21 may be employed, as shown in Fig. 1. The push pin is connected to a casing 18 which is axially displaceable in the handle-shaft. Lugs 22 on the casing take into grooves 23 in the lock-spindle to prevent rotary displacement relative to the latter. Lugs 19 on the casing 25 take into notches 20 in the boss of the inner handle, thereby holding the handle in various positions relative to the spindle. The handle is released from the lugs 19 by a pressure on the push pin 21.

30 According to another construction (Fig. 14) a spring 71 is employed which acts on the ring 14 and tends to turn the handle in the arresting position. The lug 19 stops the handle in either of three positions by engagement with the apertures 82 in a plate 76 secured to the boss of the inner handle. When it is desired to turn the handle from the normal position into position for arresting the outer handle, it is only necessary to 35 depress the push pin 21. The handle will then be turned by the spring until the lug 19 snaps into engagement with the next aperture 82. If a locking of the bolt 7 is desired, the push pin is again depressed so that the spring can bring the handle to the 40 extreme position in which the arm 13 is put into engagement with the notch 33. The end of the lug 19 is bevelled in one direction so that when the handle is turned for 45 operating the bolt, the lug 19 is automatically retracted and released from the aperture 82.

50 A pin 4 (Fig. 16) which is fitted in the handle-shaft and takes into a groove of the lock spindle for retaining the shaft on the spindle may be provided with a triangular head, as shown in Fig. 17, adapted to snap into engagement with apertures in a spring 55 secured to the escutcheon or to the door 60 so as to hold the handle yieldingly in the different positions.

65 A modified device is shown in Figs. 14 and 14^a, and consists of a ring 72 which is axially slidable on the handle-shaft. This ring has pins 73 which take through the shaft 81

into a zig-zag groove 75, 85, 86 in the lock-spindle. The shoulders formed by the groove serve as abutments for the pins 73, the ring being moved axially for bringing the pins into engagement with the different 70 shoulders. In Fig. 14 the spring 71 is applied to the outside of the ring 14 and abuts against a stud 77 in the lock-casing. In Fig. 16 a spring 78 is arranged for the same purpose inside the ring 56 about a reduced portion 79 of the lock-spindle 3.

The lock according to Fig. 7 has a pivoted bolt 36 such as used for sliding doors and has a slide 30 which is operated by means of the door-handles as previously described. 80 The slide has a bevelled end surface 37 which strikes against a corresponding shoulder 38 on the bolt, thereby turning the bolt about the pivot 35. A spring 34 tends to hold the bolt and slide in the normal position. A key-mechanism 39, as previously described, may be used for lifting the bolt-head by means of the barrel-arm which can also be applied to a hooked lug 41 on the bolt for arresting the latter. The lock-mechanism may be 85 adapted for arresting the slide 30 and thereby the outer door-handle, the bolt being then free to engage automatically when the door is slammed. This is shown by dotted lines in Fig. 7, the slide being provided with a lug 90 40 for engagement with the barrel-arm which also acts on the bolt for turning the latter about the pivot 35. The same lock may be applied to double-doors, the bolt being then provided with a laterally engaging head 100 such as shown in Fig. 10. The striking plate is shown in Fig. 9.

According to the modification shown in Fig. 13 the outer handle is arrested by means of a pivoted catch 51 which snaps 105 over a lug 50 secured to the follower 6. When the inner handle is used, an arm 52 on the ring 14 engages the catch 51 and turns it about its pivot so as to release the follower before the latter is engaged by the 110 edge of the ring for operating the bolt. In the normal position of the inner handle, the catch 51 is held by the arm 52 clear of the arm 50. The arm 13 on the ring 14 can be 115 used as previously described for arresting the bolt. From the outside the door can be opened by means of a key when the bolt is not arrested by the arm 13. The inner handle can be set by means of the lock-plate 76 (Fig. 15) so that the outer handle is normally locked by the catch 51. The release of the outer handle can then be effected electrically. For this purpose the catch is pivoted to the core 62 of a solenoid 61, and to a double-armed lever 63. When the solenoid is excited, the catch 51 is raised together with the core, and the lever 63 is turned about its pivot. Another catch 66 having a bevelled head with a nose 67, snaps over the end 64 of the lever 63 under 120 125 130

the influence of the spring 65 and retains the catch 51. At the same time a clapper 69, connected to the catch 66, strikes against a bell 70 to indicate that the door can be opened. As the bolt is withdrawn, a lug 68 on the same strikes against the catch 66 so as to release the catch 51 which then again arrests the outer handle.

In the modification shown in Fig. 16 the 10 follower 55 is fitted on the square portion of the lock-spindle, the ring 56 being fitted on a cylindrical portion and coupled by means of pins 12 to the shaft of the inner handle. The ring 56 may consist of a mere 15 prolongation of the hollow handle-shaft.

The cylindrical portion of the lock spindle has a lug 57 (Figs. 19 and 20) which is engaged by the edge 58 of the ring 56 for operating the bolt. A catch 51 is arranged 20 so as to take over the lug 57 and arrest the handle. Normally the catch is held by a lug 52 on the ring 56 as shown in Fig. 19 so that either handle can be used for opening the door. When the ring is set by means 25 of the inner handle in the position shown in Fig. 20, the outer handle is locked. To release the handle an electromagnet may be used, as indicated.

The spindle 5 may be arranged underneath the bolt 7 in which case a lug 17 on the follower 55 engages the bolt as shown in Fig. 18.

In the lock according to Figs. 1 and 2, which is suitable for the doors of lavatories 35 and telephone cabinets, an indicator disc 26 is provided for showing in a window 80 whether the cabinet or the like is engaged or vacant. The disc is mounted on a sleeve 27 which is rotatable about the lock-spindle 40 and which has a lug 29 in engagement with a notch 11 in the ring 14. The disc will thus follow the adjustments of the inner handle. As the doors to which the locks have to be applied may vary in thickness, 45 the arrangement of Fig. 4 may be resorted to, the disc having a lug 28 which takes into a longitudinal slot in the sleeve so as to engage therewith in any position of axial adjustment.

50 I claim:—

1. In a door-lock of the character described, the combination with the outer door handle of a follower connected to the outer door-handle and an inner handle 55 which is rotatable relative to the outer one, a rotatable ring coupled to the inner handle so as to follow its movements, means for causing the ring to engage and turn the follower in one direction of movement of the 60 inner handle, and means for causing the ring to arrest the lock-mechanism when the inner handle is turned in the opposite direction.

2. In a door-lock of the character described, the combination with the outer door

handle of a follower having an operating arm connected to the outer door-handle and with an inner handle which is rotatable relative to the outer one, of a rotatable ring coupled to the inner handle so as to follow its movements, the ring being arranged about the follower and provided with a slot to admit the operating arm of said follower and to allow the relative rotary displacement of the two handles, the follower 70 arm being engaged at one end of the slot for withdrawing the bolt when the handle is turned in the usual manner, and an arm on the ring arranged so as to arrest the lock-mechanism, when the inner handle is turned 75 in the direction opposite to the usual one.

3. In a door-lock of the character described, the combination with the outer door handle of a follower connected to the outer door-handle and with an inner handle 80 which is rotatable relative to the outer one, of a rotatable ring coupled to the inner handle so as to follow its movements, means for causing the ring to engage and turn the follower in one direction of movement of the 85 inner handle, means for causing the ring to arrest the lock-mechanism when the inner handle is turned in the opposite direction, and means for securing the inner handle relative to the outer one in arrest- 90 position, substantially as set forth.

4. In a door-lock of the character described, the combination with the outer door handle of a follower connected to the outer door handle and with an inner handle which 100 is rotatable relative to the outer one, of a rotatable ring coupled to the inner handle so as to follow its movements, means for causing the ring to engage and turn the follower in one direction of movement of the inner 105 handle, means for causing the ring to arrest the lock-mechanism, when the handle is turned in the opposite direction, and means for securing the inner handle to the spindle of the outer one so as to retain it in arrest- 110 position.

5. In a door-lock of the character described, the combination with the outer door handle of a follower connected to the outer door-handle and with an inner handle which 115 is rotatable relative to the outer one, of a rotatable ring coupled to the inner handle so as to follow its movements, means for causing the ring to engage and turn the follower in one direction of movement of the 120 inner handle, means for causing the ring to arrest the lock-mechanism, when the inner handle is turned in the opposite direction, and a spring pressed push pin guided longitudinally on the spindle of the outer handle 125 and adapted to engage the inner handle in its position of reversal.

6. In a door-lock of the character described, the combination with the outer door handle of a follower connected to the outer 130

door-handle and with an inner handle which is rotatable relative to the outer one, of a rotatable ring coupled to the inner handle so as to follow its movements, means for 5 causing the ring to engage and turn the follower in one direction of movement of the inner handle, means for causing the ring to arrest the lock-mechanism when the inner handle is turned in the opposite direction, a 10 spring tending to hold the inner handle in arresting position, and means for retaining the inner handle in the normal position.

7. In a door-lock of the character described, the combination with the outer door handle of a follower connected to the outer door-handle and with an inner handle which is rotatable relative to the outer one, of a ring coupled to the inner handle so as to follow its movements, means for causing the 15 ring to engage and turn the follower in one direction of movement of the inner handle, means for causing the ring to arrest the bolt-mechanism when the inner handle is turned in the opposite direction, a spring tending 20 to hold the inner handle in arresting position, and a spring-pressed push pin guided longitudinally on the spindle of the outer handle and adapted to engage normally the inner handle in its various positions relative 25 to the outer one.

8. In a door-lock of the character described, the combination with the outer door handle of a follower connected to the outer door-handle and with an inner handle which 30 is rotatable relative to the outer one, of a rotatable ring coupled to the inner handle so as to follow its movements, means for causing the ring to engage and turn the follower in one direction of movement of the inner handle, means for causing the ring to arrest the bolt-mechanism, when the inner handle is turned in the opposite direction, a pin connected to the shaft of the inner handle, an escutcheon engaging such pin so as 35 to prevent axial movement of the handle, and a spring having apertures with which to engage the pin so as to secure the inner handle in arresting position.

9. In a door-lock of the character described, the combination with the outer door handle of a follower connected to the outer door-handle and with an inner handle which is rotatable relative to the outer one, of a rotatable ring coupled to the inner handle so 40 as to follow its movements, means for causing the ring to engage and turn the follower in one direction of movement of the inner handle, means for causing the ring to arrest the bolt mechanism when the inner handle is turned in the opposite direction, and an indicator disc arranged at the outside of 45 the door and coupled to the inner handle.

10. In a door-lock of the character described, the combination with the outer door handle of a follower connected to the outer

door-handle and with an inner handle which is rotatable relative to the outer one, of a rotatable ring coupled to the inner handle so as to follow its movements, means for causing the ring to engage and turn the follower 70 in one direction of movement of the inner handle, means for causing the ring to arrest the bolt-mechanism when the inner handle is turned in the opposite direction, an indicator disc arranged outside the door 75 and coupled to the inner handle so as to indicate whether the bolt-mechanism is operable or not, and a window covering such disc, substantially as set forth.

11. In a door-lock of the character described, the combination with the outer door handle of a follower connected to the outer door-handle and with an inner handle which is rotatable relative to the outer one, of a rotatable ring coupled to the inner handle 80 so as to follow its movements, means for causing the ring to engage and turn the follower in one direction of movement of the inner handle, means for causing the ring to arrest the bolt-mechanism when the inner handle is turned in the opposite direction, a sleeve arranged on the spindle of the outer handle and coupled to the inner handle 85 so as to partake in its movements and an indicator disc arranged on such sleeve so as to be axially adjustable and so as to be visible from the outside for indicating whether the bolt-mechanism is operable or not, substantially as set forth.

12. In a door-lock of the character described, the combination with the outer door handle of a follower connected to the outer door-handle and with an inner handle which is rotatable relative to the outer one, of a slide controlled by the follower and serving 100 as operating means between the follower and the lock-bolt, a rotatable ring coupled to the inner handle so as to move in unison therewith, means for causing the ring to engage and turn the follower in the normal direction of movement without affecting it in the reverse direction, and an arm on the ring adapted to arrest the slide and the outer handle when the inner handle is turned in the direction opposite to the normal one, the lock-bolt being free to move when the slide is thus arrested, substantially as and for the purpose set forth.

13. In a door-lock of the character described, the combination with the outer door handle of a follower connected to the outer door-handle and with an inner handle which is rotatable relative to the outer one, of a slide controlled by the follower and serving 110 as operating means between the follower and the lock-bolt, a rotatable ring coupled to the inner handle so as to move in unison therewith, means for causing the ring to engage and turn the follower in the normal direction of movement without affecting it 115 as and for the purpose set forth.

- in the reverse direction, and an arm on the ring adapted to engage and arrest the slide in one position and the lock-bolt in another position of reversal of the inner handle, substantially as set forth. 5
14. In a door-lock of the character described, the combination with the outer door handle of a pivoted lock-bolt, with a follower connected to the outer handle and with an inner handle which is rotatable relative to the outer one, of a slide controlled by the follower and operating the bolt by means of bevelled contact surfaces, a rotatable ring coupled to the inner handle so as to move in unison therewith, means for causing the ring to engage and turn the follower in the normal direction of movement without affecting it in the reverse direction, and an arm connected to said ring so as to engage and arrest the slide when the inner handle is reversed. 10
15. In a door-lock of the character described, the combination with the outer door handle of a follower connected to the outer door-handle and with an inner handle which is rotatable relative to the outer one, of a slide controlled by the follower and serving as operating means between the follower and the lock-bolt, a rotatable ring coupled to the inner handle so as to move in unison therewith, means for causing the ring to engage and turn the follower in the normal direction of movement without affecting it in the reverse direction, an arm on the ring adapted to engage and arrest the slide in one position and the lock bolt in another position of reversal of the inner handle, a key-mechanism for operating the bolt from the outside when the bolt-slide is thus arrested, and a lug on the bolt co-operating with said key-mechanism for arresting the bolt by means of the key. 15
16. In a door-lock of the character described, the combination with the outer door handle of a follower connected to the outer door-handle and with an inner handle which is rotatable relative to the outer one, of a slide controlled by the follower and serving as operating means between the follower and the lock-bolt, a rotatable ring coupled to the inner handle so as to move in unison therewith, means for causing the ring to engage and turn the follower in the normal direction of movement without affecting it in the reverse direction, an arm on the ring adapted to engage and arrest the slide in one position and the lock-bolt in another position of reversal of the inner handle, a key-operated slotted casing, a pivoted arm arranged in the slot of said casing so as to be turned by the casing when engaged at the ends of the slot in one direction of operating the bolt when the slide is arrested and in the other direction for arresting the bolt, substantially as set forth. 20
17. In a door-lock of the character described, the combination with the outer door handle of a follower connected to the outer door-handle and with an inner handle which is rotatable relative to the outer one, of a slide controlled by the follower and serving as operating means between the follower and the lock-bolt, a rotatable ring coupled to the inner handle so as to move in unison therewith, means for causing the ring to engage and turn the follower in the normal direction of movement without affecting it in the reverse direction, an arm on the ring adapted to engage and arrest the slide in one position and the lock bolt in another position of reversal of the inner handle, a key-mechanism of the revolving-barrel type, and an arm turned by said mechanism and arranged so as to operate the bolt when turned in one direction and arrest the bolt when turned in the other direction, the barrel having two sets of locking-pins so that it can be fixed both in arresting position and out of it. 25
18. In a door-lock of the character described, the combination with the outer door handle of a follower connected to the outer handle, and with an inner handle which is rotatable relative to the outer one, of a rotatable ring coupled to the inner handle so as to move in unison therewith, means for causing the ring to engage and turn the follower in the bolt-operating direction, the ring being free in the opposite direction, a lug on the follower, a pivoted catch adapted to engage such lug for arresting the outer handle, and means for releasing the lug when the inner handle is used for operating the lock. 30
19. In a door-lock of the character described, the combination with the outer door handle of a follower connected to the outer handle, and with an inner handle which is rotatable relative to the outer one, of a rotatable ring coupled to the inner handle so as to move in unison therewith, means for causing the ring to engage and turn the follower in the bolt-operating direction, the ring being free in the opposite direction, a lug on the follower, a pivoted catch adapted to engage such lug for arresting the outer handle, and a lug on the rotatable ring adapted to engage such catch so as to release the follower when the inner handle is used for operating the lock. 35
20. In a door-lock of the character described, the combination with the outer door handle of a follower connected to the outer handle, and with an inner handle which is rotatable relative to the outer one, of a rotatable ring coupled to the inner handle so as to move in unison therewith, a ring arranged rotatably about the follower, the follower having a bolt-operating arm projecting through a circumferential slot in the ring so that the arm can be engaged at one 40

- end of the slot for operating the bolt by means of the inner handle, and means for fixing the inner handle with the opposite end of the slot in engagement with the lug so as to arrest the lock-mechanism.
21. In a door-lock of the character described, the combination with the outer door handle of a follower connected to the outer handle, and with an inner handle which is rotatable relative to the outer one, of a rotatable ring coupled to the inner handle so as to move in unison therewith, a ring arranged rotatably about the follower, the follower having a bolt-operating arm projecting through a circumferential slot in the ring so that the arm can be engaged at one end of the slot for operating the bolt by means of the inner handle, means for fixing the inner handle with the opposite end of the slot in engagement with the lug so as to arrest the lock-mechanism, and an arm on the rotatable ring adapted to engage a notch on the bolt when in arresting position as an additional security.
22. In a door-lock of the character described, the combination with the outer door handle of a follower connected to the outer door-handle and with an inner handle which is rotatable relative to the outer one, of a rotatable ring coupled to the inner handle and adapted to engage and turn the follower when the inner handle is turned for operating the lock, the ring being free to allow the inner handle to be turned into an upright position, a lug on the follower, a catch adapted to engage such lug so as to arrest the follower, a lug on the rotatable ring adapted to hold the catch out of arresting position when the inner handle is in lock-operating position, and means for operating the catch electrically so as to release the follower when the inner handle is turned into the upright position.
23. In a door-lock of the character described, the combination with the outer door handle of a follower connected to the outer door-handle and with an inner handle which is rotatable relative to the outer one, of a rotatable ring coupled to the inner handle and adapted to engage and turn the follower when the inner handle is turned for operating the lock, the ring being free to allow the inner handle to be turned into an upright position, a lug on the follower, a catch adapted to engage such lug so as to arrest the follower, a lug on the rotatable ring adapted to hold the catch out of arresting position when the inner handle is in lock-operating position, a solenoid arranged so as to act on the catch when excited and release the follower when the inner handle is in upright position, means for retaining the catch in releasing position, and means for returning it to arresting position by the withdrawal of the lock-bolt.
24. In a door-lock of the character described, the combination with the outer door handle of a follower connected to the outer door-handle and with an inner handle which is rotatable relative to the outer one, of a rotatable ring coupled to the inner handle and adapted to engage and turn the follower when the inner handle is turned for operating the lock, the ring being free to allow the inner handle to be turned into an upright position, a lug on the follower, a catch adapted to engage such lug so as to arrest the follower, a lug on the rotatable ring adapted to hold the catch out of arresting position when the inner handle is in bolt-operating position, a solenoid arranged so as to act on the catch when excited and release the follower when the inner handle is in upright position, means for retaining the catch in releasing position, means for retaining it in arresting position by the withdrawal of the lock-bolt, and a clapper connected to the arresting catch so as to ring a bell when the catch is operated.
25. In a door-lock of the character described, the combination with the outer door handle of a follower connected to the outer door-handle and with an inner handle which is rotatable relative to the outer one, of a rotatable ring coupled to the inner handle and adapted to engage and turn the follower when the inner handle is turned for operating the lock, the ring being free to move independently in the reverse direction, means enabling the ring to arrest the outer handle in one position of reversal, means enabling the ring to arrest the lock-bolt in another position of reversal, a spring tending to hold the ring in the extreme reversed position, and means for securing the ring in lock-operative as well as in outer handle arresting position.
26. In a door-lock of the character described, the combination with the outer door handle of a follower connected to the outer door-handle and with an inner handle which is rotatable relative to the outer one, of a rotatable ring coupled to the inner handle so as to move in unison therewith, means for causing the ring to engage and turn the follower when the inner handle is turned for operating the lock, the ring being free to move independently in the reversed direction, means enabling the ring to arrest the outer handle in one position of reversal, means enabling the ring to arrest the lock-bolt in another position of reversal, a spring tending to hold the ring in the extreme reversed position, a catch for holding the ring in bolt-operative as well as in outer handle arresting position, said catch having a bevelled engaging surface causing it to be automatically released when

the handle is pressed for opening the door, and a spring-push for disengaging the catch from the ring, substantially as set forth.

27. In a door-lock of the character described, the combination with the outer door handle of a follower connected to the outer door-handle and with an inner handle which is rotatable relative to the outer one, of a rotatable ring coupled to the inner handle so as to move in unison therewith, a ring arranged beside the follower rotatably about the spindle, means for causing the ring to engage and turn the spindle thus turning the follower when the inner handle is turned for operating the bolt, the ring being free to move independently in the reversed direction, means enabling the ring to arrest the outer handle in one position of reversal, means enabling the ring to arrest the lock-bolt in another position of reversal, a spring arranged inside the ring on a reduced portion of the bolt-spindle and tending to hold the ring in the extreme reversed position, and means for securing the ring in bolt-operative as well as in outer handle arresting position.

28: In a door-lock of the character described, the combination with the outer door handle of a follower connected to the outer door-handle and with an inner handle which is rotatable relative to the outer one, of a prolongation on the shaft of the inner handle forming a ring such ring being adapt-

ed to engage and turn the follower when the inner handle is turned for operating the bolt, the ring having an arm adapted to arrest the bolt-mechanism when the inner handle is turned in the opposite direction.

29. In a door-lock of the character described, the combination with the outer door handle of a follower connected to the outer door-handle and with an inner handle which is rotatable relative to the outer one, of a rotatable ring coupled to the inner handle so as to move in unison therewith, means for causing the ring to engage and turn the follower when the inner handle is turned for operating the lock, means on the ring for arresting the bolt-mechanism when the inner handle is turned in the opposite direction, a spring tending to hold the ring in arresting position, a longitudinally adjustable ring arranged on the shaft of the inner handle, and pins on said latter ring arranged so as to take through the shaft into a zig-zag groove in the bolt-spindle for arresting the inner handle in different positions relative to the spindle by engagement with the shoulders formed by the zig-zag groove.

In testimony whereof I affix my signature in the presence of two witnesses.

WILH. HÜTTEMANN.

Witnesses:

AUG. BAUER,
M. ENGELS.
